DESIGN FOR A COFFEE URN

Isaac D. Richheimer, New York, N. Y.

Application July 12, 1934, Serial No. 52,557

Term of patent 14 years

To all whom it may concern:

Be it known that I, Isaac D. Richheimer, a citizen of the United States, and a resident of New York, in the county of New York and State of New York, have invented a new, original, and ornamental Design for a Coffee Urn, of which the following is a specification, reference being had to the accompanying drawing, forming part thereof.

The bowl shaped member is formed with notches to receive the base of the spout and the lower end of the handle of the pot.

I claim:

The ornamental design for a coffee urn as shown and described.

ISAAC D. RICHHEIMER.
